4 Claims

ABSTRACT OF THE DISCLOSURE

Clamping mechanism including a frame and a pair of opposed relatively movable arms mounted thereon for movement toward and away from one another. The arms include a short arm mounted on the frame through an arm base that permits shifting of the arm along a substantially straight path on the frame, and further includes a long arm mounted on the frame through mounting structure which accommodates both translation of the long arm back and forth on the frame, and swinging of the arm's outer end along a flattened arcuate path toward and away from the short arm.

This invention relates to clamping mechanism, and more particularly, to such mechanism which may be used conveniently to clamp onto loads of widely different sizes. For purposes of illustration only, and not with any intention to limit other uses of the invention, the same as described herein relates to a lift truck attachment for handling paper rolls and similar objects.

Clamping mechanism for handling paper rolls and the like typically comprises a frame, a pair of opposed, relatively movable arms mounted on the frame for movement toward and away from one another, and clamping pads mounted adjacent the extremities of the arms which clamp against the sides of a roll.

Paper rolls may vary considerably in outside diameter. Thus, the arms of such mechanism should be shiftable over a wide range, whereby they are able to encompass the many different sizes of rolls that are commonly handled. To obtain maximum stability for each size of roll that is clamped onto, the clamping pads should grip the roll as nearly as possible on diametrically opposite sides of the roll. Any deviation from diametrical clamping should be minimal.

Paper rolls having relatively large diameters may, when clamped onto, extend into and occupy much of the region bounded by the frame and arms of the clamping mechanism. Accordingly, the mechanism should be so designed that this region is free of obstructions.

Since the mechanism may have to perform at times in confined spaces, the frame mounting the arms should have the smallest possible overall length. Excessive length in any guide bars that slidably support an arm should be avoided, since such tend to project beyond the ends of the mounting frame with the arms moved close together. It has been proposed, therefore, to provide an organization wherein at least one arm not only translates but also pivots when brought toward the opposite arm. This invention features an improvement in such an organization and the way in which such arm is pivoted while also translating toward the other arm.

Another factor to consider is that at times it is desirable to use the arms of the clamping mechanism backhandedly, i.e., as an agency for moving an object by moving the outer back side of an arm outwardly against the object. To enable this type of operation, the mountings for the arms should be such that they may be shifted outwardly under power while held positively on the frame in the clamping mechanism.

2

A general object of the present invention is to provide novel mechanism for clamping onto loads, such as paper rolls, which takes care of the above considerations in a practical and satisfactory manner.

More particularly, an object of the invention is to provide improved clamping mechanism, including a frame and opposed relatively movable arms mounted on the frame, which can clamp onto the sides of loads having widely differing sizes.

Another object is to provide such mechanism, which is compact in size, which requires minimal space for movement of its arms, and which provides proper clearance for loads in the region bounded by the frame and arms.

According to the invention, the mechanism includes both a long arm and a short arm, each carrying a clamping pad adjacent its outer extremity. Each arm is movable. With relative movement of the arms toward one another during clamping, the clamping pads come substantially against diametrically opposite sides of a load placed between the arms. With the usual sizes of loads that are handled, any deviation from exact diametrical clamping is minimal. Toward this end, the long arm is mounted in such a manner that its outer extremity, with movement of the arm toward the short arm, moves in an arcuate path which first substantially parallels and then is directed inwardly toward the frame mechanism.

Characterizing a preferred embodiment of the invention, the long arm, intermediate its inner and outer ends, is pivoted to an arm base which is mounted for movement along a substantially straight path on the frame. The inner extremity of the long arm is mounted on the frame through novel link and pivot means, which affords arcuate movement of such end about an axis spaced from the pivot axis provided by the connection between the long arm and arm base. With such construction, during movement of the long arm, the clamping pad thereon travels along the above-mentioned arcuate path which, because of the link and pivot means, is somewhat straighter than a true circular path. Accordingly, within the full range of relative movement permitted the arms, the clamping pads tend to come against diametrically opposite sides of loads placed between the arms.

A further object of the invention is to provide such mounting structure for the long arm which permits the arm to be used backhandedly while positively held.

These and other objects and advantages attained by the invention will become more fully apparent as the description which follows is read in conjunction with the accompanying drawings, wherein:

FIG. 1 is a side elevation, illustrating the front portion of a lift truck carriage on which is mounted clamping mechanism constructed according to the invention, such clamping mechanism including a pair of clamping arms disposed one above the other with the clamping mechanism upright as shown; and

FIG. 2 is a view, partly in cross section, taken along the line 2—2 in FIG. 1.

Turning now to the drawings, indicated generally at 10 is load clamping mechanism taking the form of what is called a paper roll grab. The mechanism includes a pair of opposed relatively movable clamping arms, including a short arm 12 and a long arm 14 mounted on a frame 16 with the arms extending out from the front of the frame. The mechanism is positioned with arm 14 disposed above arm 12.

The rear of frame 16 is suitably attached to revolvable structure 18 of conventional construction provided to enable rotation of the frame and arms about a substantially horizontal axis. In this way the clamping mechanism may be used to upend a roll, or otherwise handle rolls resting on their ends or on their sides. Structure 18 includes a pair of circular, relatively rotatable plates 18a,

18b. A suitable power drive unit 20 is provided for rotating plate 18b relative to plate 18a. Brackets 22a, 22b on the back of plate 18a secure structure 18 on an attaching plate 24 which is usually found on the forward part of the elevatable carriage in a lift truck.

Frame 16 includes two pairs of elongated laterally-spaced tubes, comprising a first set of tubes or guides 28 and a second set of tubes or guides 30. As can be seen in FIG. 2, tubes 30 are positioned laterally outwardly of tubes 28. Tubes 28, 30 have elongated slots 28a, 30a, respectively, extending along their lengths. Slots 28a are located adjacent the upper ends of tubes 28 in the drawings, and open onto the forward sides and upper ends of the tubes. Slots 30a are located adjacent the lower ends of tubes 30, and open onto the forward sides and lower ends of the tubes. Tubes 28 are somewhat longer than tubes 30, and have their upper ends extending upwardly beyond the upper ends of tubes 30.

The upper ends of tubes 28 are secured together by an elongated end plate 32 which includes, adjacent its opposite ends, bores 32a receiving the upper ends of the tubes. The plate has slots 32b which are aligned with previously-mentioned slots 28a, and which extend from the front edge of the plate into bores 32a. Between bores 32a, plate 32 further includes an opening 32c and a bore 32d.

The lower ends of both pairs of tubes are secured together through an elongated end plate 34. Bores 34a in the plate receive the lower ends of tubes 30, and bores 34b receive the lower ends of tubes 28. Slots 34c aligned with slots 30a, extend from the front edge of the plate into bores 34a. Between bores 34b the plate includes an opening 34d and a bore 34e, which are positioned directly opposite previously-mentioned bore 32d and opening 32c respectively.

Turning to the construction of the arms, and considering first of all arm 12, the arm has a butt end 12a adjacent the frame and a tip end 12b located forwardly of the frame. In side outline, the arm tapers progressing from the butt end toward the tip end. The arm comprises outer and inner cover plates 36, 38 respectively. Adjacent the tip end of the arm, the cover plates are closely spaced, and progressing toward the butt end the plates diverge and are joined to side plates such as side plate 40. Joined to the butt end of the arm and forming part of what is referred to as an arm base is a back plate 42. Fastened to the back plate is a rearwardly projecting ear 43 having a bore 43a.

Arm 12 is provided with a pressure pad 44 which is connected to the tip end of the arm through a hinge connection 46. The back edge of the pressure pad (the edge nearer frame 16) is urged toward the arm by a suitable biasing means indicated generally at 48 which interconnects the pad and arm.

Further describing the arm base which mounts arm 12 for movement along the frame, joined to back plate 42 are a pair of spaced-apart mounting members 50. Each mounting member includes a bar or slide portion 50a slidably received within the interior of one of tubes 30, and a carrier portion 50b. Members 50, tubes 30 and slots 30a accommodate shifting of arm 12 along a substantially straight path toward and away from arm 14. The slots in tubes 30 receive portions 50b with arm 12 moved inwardly on frame 12.

Considering arm 14, it includes, along each side thereof, a pair of elongated, angular arm members 52 having the side profile illustrated in FIG. 1. Joined to the upper and lower faces of members 52 are cover plates 54, 56, respectively. The cover plates include forward end portions 54a, 56a which extend across the arm and are spaced close together to give a thin side profile to the forward end of the arm, central portions 54b, 56b which also extend across the arm and diverge from one another progressing rearwardly along the arm, and inner rear end portions 54c, 56c.

Arm 14 is provided with a pressure pad 58 which is

similar to pad 44 on arm 12. Pad 58 is connected to the forward end of the arm through a hinge connection 60. Biasing means 62, which may be similar to biasing means 48, connects pad 58 to the arm, and urges the rear edge of the pad toward the arm.

Considering the mounting for arm 14 on the frame, an arm base for the arm is indicated generally at 64. Base 64 includes a pair of cover plates 66, 68 joined to side plates, such as side plate 70 (FIG. 1). Secured adjacent the outer ends of plates 70 are laterally-spaced bearings 72 (FIG. 2). The inner ends of plates 66, 68, 70 are joined to an elongated back plate 74. A rearwardly projecting ear 75 having a bore 75a is secured to the back of back plate 74.

Arm base 64 further includes a pair of spaced-apart arm mounting members 76 which are similar in construction to previously-described members 50. Thus, members 76 include bar or slide portions 76a slidably received within the interiors of tubes 28, and carrier portions 76b. The carrier portions are suitably joined to the back face of plate 74 adjacent opposite ends of the plate. Members 76, tubes 28 and slots 28a accommodate translating of the arm base along a substantially straight path between extended and retracted positions on the frame, toward and away from arm 12. The slots in tubes 28 receive portions 76b with arm base 64 moved toward its retracted position on the frame.

Arm base 64 is connected to arm 14, intermediate the inner and outer ends of the latter, through an elongated pivot pin or pivot means 78. Pin 78 extends through previously-mentioned bearings 72 in the arm member, through appropriate aligned bores provided in arm members 52, and through suitable bearings, such as those shown at 80 (FIG. 2), mounted on the arm in the space between end portions 54c, 56c of plates 54, 56. Pin 78 enables pivoting of arm 14 about an axis extending transversely of the arm.

Considering FIG. 2, suitably mounted adjacent the upper ends of tubes 30 are lugs 82. The inner extremities 40 of arm 14 are connected to these lugs through elongated links 84 and pivot pins, or journals, 86, 88. Pins 86 connect one set of ends of links 84 to the inner ends of arm members 52 on opposite sides of the frame. Pins 88 connect the other set of ends of the links to lugs 82. The 45 respective pivot axes provided by pins 86, 88 on either side of the frame are aligned.

Lugs 82, links 84, and pins 86, 88 comprise anchoring means for the inner extremities of arm 14. Such links and pins afford restricted arcuate movement of the inner 50 extremities of the arm about the pivot axis provided by pins 88. It will be noted that this axis is parallel to but spaced from the pivot axis provided for the arm by pin 78.

Rams or power-operated means for shifting the arms toward and away from each other are shown at 90, 92. 55 Considering ram 90, the cylinder of the ram has a threaded axial projection 90a at its upper end in the drawings which extends upwardly through bore 32d in plate 32. The ram is mounted on plate 32 by means of a nut 94 screwed onto projection 90a. The rod of the ram extends downwardly through opening 34d in plate 34 and through bore 43a in ear 43. The lower end of the rod is secured to ear 43 by means of fasteners 96.

Considering ram 92, the cylinder of the ram has a 60 threaded axial projection 92a at its lower end in the drawings which extends downwardly through bore 34e in plate 34. The ram is mounted on plate 34 by means of a nut 98 which is screwed onto projection 92a. The rod of the ram extends upwardly through opening 32c in plate 32 and through bore 75a in ear 75. The upper end of the rod is secured to ear 75 by fasteners 100.

Describing more fully the movement producable in arm 14 with shifting of arm base 64, such shifting causes pivot pin 78 to travel along a substantially straight path, 65 paralleling but disposed in front of tubes 28. Movement

of pin 78 causes the distance between the axis provided by the pin, and the common axis of pins 88, to change.

Such changing of the distance between these two axes is accommodated and accompanied by swinging of links 84 about pins 88. This, in turn, produces corresponding swinging of the inner extremities of the arm, where such are connected to the links through pins 86. More particularly, swinging of the links produces arcuate movement of the inner ends of arm 14 about the pivot axis provided through pins 88. The maximum arcuate movement of links 84 (and hence the inner extremities of arm 14) required to accommodate shifting of arm base 64 from its fully extended position to its fully retracted position, is illustrated as angle A in FIG. 1.

Further, with movement of arm base 64 from its extended to its retracted position on the frame, it will be noted that the inner extremities of arm 14 move first rearwardly and then forwardly relative to the frame along a substantially horizontal path, with such horizontal movement being accommodated by pivoting of links 84. As a consequence, the forward end of the arm travels along an arcuate path, such as that indicated at P. Path P is not a true circular path, but is instead flattened appreciably due to the movement just described produced in the inner extremities of arm 14. This feature of the invention enables the clamping pads on the arms, regardless of a load's diameter, to clamp onto all loads substantially on diametrically opposite sides.

Explaining now how the clamping mechanism described may be used to handle paper rolls of different diameters, in FIG. 1 several rolls are illustrated in dash-dot outline. At 102 is a relatively large roll; at 104 a medium-sized roll; and at 106 a relatively small roll.

To grab any one of such rolls, the clamping arms, through operation of rams 90, 92, are shifted apart a sufficient distance to receive the roll, and are maneuvered whereby they are placed on substantially opposite sides of the roll. The rams are then operated to shift the pressure pads 44, 58 inwardly against the roll.

The positions of the arms required to clamp onto roll 102 are substantially those shown for the arms in solid outline; the positions required to clamp onto roll 104 are shown in dash-dot outline at 12A, 14A; and the positions required to clamp onto roll 106 are shown at 12B, 14B. It will be noted that for each of the rolls illustrated, the clamping pads of the arms are disposed substantially on diametrically opposite sides of the roll. As can be seen, any deviation from true diametrical clamping is minimal.

Thus, the mechanism provided herein can readily handle rolls having a wide range of outside diameters, with nearly true diametrical clamping producible for each size roll. Only a minimal amount of space is required to accommodate movement of arms 12, 14. With guide tubes 28 disposed inwardly of tubes 30 and having their upper ends extending beyond those of the latter, and with pivot parts 82 located as shown, a relatively compact, stable construction results.

It will be noted from FIG. 1 that the space bounded by the arms and frame is free of obstructions that might interfere with clamping of a roll. This space remains clear regardless of the positions of the arms and arm mountings.

With arm 14 mounted as shown, and mechanically linked at all times to the frame, the arm can readily be employed backhandedly to push a load to one side. Further explaining, let it be assumed that the clamping mechanism has been rotated by operation of revolvable structure 18 to shift the frame from the vertical position shown into a horizontal position with the arms then being laterally spaced from each other in front of the lift truck. A roll or other object may then be shifted to one side through the expedient of extending arm 14 laterally outwardly with cover plate 54 on the back side of the arm contacting the roll. The arm will not give way during such

an operation, since at all times, the mounting for the arm functions to hold it in a predefined position relative to the arm base and frame.

While an embodiment of the invention has been described herein, it is appreciated that variations and modifications may be made without departing from the spirit of the invention. It is desired to cover all such variations and modifications that would be apparent to one skilled in the art and which come within the scope of the appended claims.

It is claimed and desired to secure by Letters Patent:

1. In clamping mechanism comprising a frame and a first arm mounted on and projecting forwardly of said frame,

an arm base on said frame occupying an extended position which is remote from said first arm, said arm base being mounted on said frame for movement toward said first arm along substantially a linear path to assume a retracted position on said frame, another arm opposite the first arm projecting forwardly of said frame having a rear end disposed adjacent the frame and a forward free end,

pivot means mounting said other arm on said arm base at a point located between opposite ends of the other arm accommodating pivoting of said other arm relative to the arm base about an axis extending transversely of the other arm,

said rear end of said other arm during movement of the arm base from its extended to its retracted position undergoing an oscillation by moving first rearwardly and then forwardly in a course extending transversely of said linear path to effect flattened curvilinear movement in the free end of said other arm throughout such movement to a retracted position,

and anchoring means anchoring said rear end of said other arm on said frame throughout movement of the arm base from its extended to its retracted position generating such oscillation in said rear end on movement of said other arm to its retracted position and restricting movement of said rear end to movement along said transverse course.

2. The clamping mechanism of claim 1, wherein said anchoring means anchoring said rear end of said other arm on said frame comprises a link pivotally connected at spaced-apart points to said frame and to said other arm.

3. In clamping mechanism comprising an elongated frame and a first arm mounted on said frame adjacent one of the frame's ends and projecting forwardly of said frame,

an arm base mounted on said frame adjacent the other end of the frame for translational movement toward and away from said first arm,

another arm opposite the first arm projecting forwardly of said frame and having a rear end disposed adjacent the frame and a forward free end,

pivot means mounting said other arm on said arm base at a point located between opposite ends of the other arm accommodating pivoting of said other arm relative to the arm base about an axis extending transversely of the other arm,

at least one link adjacent the side of the frame generally paralleling the axis of the frame,

and spaced-apart journals connecting one end of said link to said frame and the other end of said link to said rear end of said other arm, respectively, whereby the link serves as an anchor for said rear end of said other arm throughout movement of said arm base while permitting restricted movement afforded by pivoting of the link.

4. Clamping mechanism comprising a frame including first and second pairs of elongated, laterally spaced, substantially parallel guides, said first pair of guides being disposed outwardly of said second pair of guides, and said second pair of guides

having a set of ends projecting beyond a set of ends of said first pair of guides,
 a first elongated arm projecting forwardly of said frame and an arm base supporting said first arm for movement along a path on said first pair of guides,
 a second elongated arm projecting forwardly of said frame, and an arm base for said second arm mounted for movement along a path on said second pair of guides toward and away from said first arm,
 pivot means mounting said second arm on its arm base at a point intermediate the second arm's opposite ends,
 and anchoring means anchoring the rear end of said second arm on said frame comprising a pair of links, each of which is pivotally connected at one loca-

tion to said rear end, and at another location to said frame, said links being disposed laterally outwardly of said projecting ends of said second pair of guides and axially beyond said set of ends of said first pair of guides.
